Patented Nov. 7, 1967

209,136

TRAVEL TRAILER

Georges Etienne Christin, Marnes-la-Coquette, France,
assignor to Etablissements Bertrand Faure, Puteaux,
Seine, France, a corporation of France
Filed Dec. 23, 1966, Ser. No. 5,166

Claims priority, application France June 24, 1966

Term of patent 14 years

(Cl. D14—3)

FIGURE 1 is a side elevational view of a travel trailer embodying my new design with the end closures in their open condition;

FIGURE 2 is a perspective view thereof with parts of the end closure collapsed;

FIGURE 3 is a perspective view thereof with one end closure open and the other end closure partially open;

FIGURE 4 is a rear end elevational view thereof;

FIGURE 5 is a perspective view of said travel trailer with the end closures thereof in their closed condition;

FIGURE 6 is a rear elevational view thereof; and

FIGURE 7 is a front elevational view thereof.

The dominant features of the design are shown in solid lines.

I claim:

The ornamental design for a travel trailer, as shown and described.
